[57] CLAIM

The ornamental design for a door chest, as shown and
described.

DESCRIPTION

FIG. 1 is a front elevational view of a door chest showing
my new design;

FIG. 2 is a top plan view thereof;

FIG. 3 is a right side elevational view thereof, the left
side being a mirror image thereof;

FIG. 4 is a sectional view taken along line 4—4 of FIG.
1.

The rear elevational view of the door chest is conven-
tionally flat and unornamented.

FIG. 3

FIG. 2

FIG. 4
